COIL WINDING DEVICE

Robert H. Petty, Las Vegas, Nev., assignor to Titanium Metals Corporation of America, New York, N.Y., a corporation of Delaware

Filed June 20, 1960, Ser. No. 37,413

5 Claims. (Cl. 153—67)

This invention relates to a coil winding device and more particularly to a device for winding uniform coils of wire of pre-determined length.

Small coils of wire of pre-determined length are often used in various analytical procedures. In such applications the wire itself may enter into some chemical reaction and it is often desirable to control the amount of metal of which the wire is fabricated by winding a coil of pre-determined length of such wire. A need exists for a device which will produce uniform coils rapidly and efficiently for such purposes.

It is therefore a principal object of this invention to provide an improved coil winding device. Another object of this invention is to provide a coil winding device capable of producing coils of wire of pre-determined length. Another object of this invention is to provide a device useful for producing uniform wire coils. Another object of this invention is to provide a coil winding device particularly adapted for producing coils of wire used in analytical procedures. These and other objects of this invention will be apparent from the following description thereof and from the annexed drawings in which:

FIG. 1 shows a general top view of a device embodying features of this invention.

FIG. 2 shows a vertical section of the device of FIG. 1 taken along the line 2—2.

FIG. 3 shows a side view of the wire guide and cutter as seen from the mandrel side.

FIG. 4 shows a detailed view, somewhat enlarged, of the portion of the device from which the finished coil is ejected after winding.

Referring now particularly to FIGS. 1 and 2, the coil winding device comprises a base 10 on which is rotatably mounted a mandrel 12. The mounting comprises pedestal 14 attached to base 10 and in which is fixed horizontal tube member 16. Mandrel 12 is fixedly attached as by bolt 18 to handle wheel 20 by means of which it may be rotated, the extending stub shaft 22 of hand wheel 20 being journaled in the end of tube member 16 as shown. Stub shaft 22 is restrained from longitudinal movement in tube member 16 by provision of slot 24 around its circumference in which is engaged the end of pin bolt 26 threaded into a top portion of pedestal 14. The end of mandrel 12 is provided with a slot 26 of size to receive the end of a length of wire to be coiled.

Slidably mounted on mandrel 12 and biased toward the slotted end thereof by spring 28 is tubular follower 30. The end of follower 30 which is inside tube member 16 is provided with a shoulder as at 32 and when follower 30 is extended fully toward the slotted end of mandrel 12, as will be more clearly seen in FIG. 4, this shoulder 32 will abut a corresponding shoulder 34 in tube member 16. The end of follower 30 is formed as a portion of reduced outside diameter as at 36.

Hand wheel 20 is provided with a suitable handle 38

2

and is also provided with one element, as indented member 40, of a click-stop, the other element being shown as round end bolt 42 threaded through pedestal 14. Preferably the end of bolt 42 is arranged to engage the indentation in member 40 at a position so that the mandrel 12 will be stopped with an open end of slot 26 facing or pointing toward the wire guide means described hereinafter. The click-stop formed by bolt 42 and indented member 40 may also provide an audible indication of the completion of a revolution or revolutions of hand wheel 20 and mandrel 12, thus providing an indication, by reference to mandrel diameter and slot length of wire coiled.

Slidably and rotatably mounted, also on base 10, is shaft 44 which is journaled through a pedestal 46 which is fixedly attached to base 10. Shaft 44 is limited in its sliding and rotating movement by provision in its surface of L-shaped slot 48 which is engaged by the end of pin bolt 50 threaded through a top portion of pedestal 46 as shown. Fixedly mounted on shaft 44 is coil cover guide 49 which is formed as a tube segment, preferably semi-circular. Thumb wheel 52 is attached to the outer end of shaft 44 for convenient actuation thereof. When shaft 44 is pushed toward mandrel 12 and rotated so that pin bolt 50 is at the end of the circumferential leg of slot 48, end face 54 of shaft 44 will abut and be thus locked against the end of mandrel 12 and will thereby close the open side of slot 26. Coil cover guide 49 is affixed to the end of shaft 44 so that when the face 54 is locked against mandrel 12, as just described, it will overlay mandrel 12 on the side remote from the wire guide means, which, as seen in FIG. 3, comprises guide bore 56 through a pedestal 58, which is in turn attached to base 10. Pedestal 58 and guide bore 56 are spaced apart from mandrel 12 and interposed therebetween is a wire cutter, comprising a blade 60 pivotably mounted as by bolt 62 on pedestal 58 and arranged so that depression of the handle 64 thereof will cause blade 60 to shear a wire emerging from the mandrel side of guide bore 56.

When shaft 44 is rotated to be in unlocked position, that is, when pin bolt 50 is at the juncture of the legs of slot 48, coil cover guide 49 will also be rotated so that it now overlays the top of mandrel 12. Sliding shaft 44 outwardly with pin bolt 50 now at the end of the longitudinal arm of slot 48, as in FIG. 4, face 54 and cover guide 49 will be moved away from the end of mandrel 12, and the side of slot 26 will be open.

In operation of the device of this invention, thumb wheel 52 is first pushed in and then rotated to the position shown in FIGS. 1 and 2. This closes the open side of slot 26 and locates cover guide 49 overlaying mandrel 12 on its side remote from the guide bore 56. At the same time spring 28 will urge follower 30 toward the slotted end of mandrel 12 and the reduced diameter end portion 36 will lie between mandrel 12 and cover guide 49. Hand wheel 20 is rotated until the end of bolt 42 is seated in the indentation of member 40 and an open end of slot 26 will now be facing or pointing toward guide bore 56.

The end of a length of wire to be coiled as at 66, is threaded through guide bore 56 and into slot 26. Handle 38 is then rotated, to form a coil on mandrel 12 as is shown in FIG. 1, cover guide 49 functioning to guide the wire to wind snugly over mandrel 12. After a pre-de-

terminated number of coil turns have been wound on mandrel 12, cutter blade handle 64 is depressed thus cutting the wire at its point of emergence from guide bore 56. Rotation of handle 38 is continued until all the wire cut off has been coiled.

It will be apparent that as the wire coil is formed on mandrel 12 it pushes back follower 30 against spring 28, the reduced diameter portion 36 being gradually moved out of the space between cover guide 49 and mandrel 12, giving way to the wire coil being formed there. After the coil is fully wound, thumb wheel 52 is rotated and moved outwardly so that pin bolt 50 is in the position in slot 48 shown in FIG. 4. Cover guide 49 will have been rotated so that as to be aligned with the top of mandrel 12 and then moved away from its position overlaying the coil in mandrel 12. At the same time the tension in spring 28 results in the end of follower 30 pushing the wire coil completely off the end of mandrel 12 and it falls free as at 68. It will be appreciated that when the end face 54 of shaft 44 is moved away from the end of mandrel 12 it opens the side of slot 26 thus permitting the wire end originally placed there to be readily removed by follower 30 pushing the whole coil off the end of mandrel 12. The rotation of cover guide 49 to a top position also allows the finished coil to fall freely when released from the mandrel 12.

The operation described above may be repeated to wind another coil and rapid production may be obtained with little effort.

The device of this invention is rapid and efficient. The unique organization wherein the follower pushes finished coils off the mandrel so that they fall free, results in high production rates. It has been found that a man winding coils of five inch lengths of platinum wire to be used for vacuum fusion analysis of metals can produce, using a device according to this invention, at a rate of over 400 coils per hour.

The click stop on the hand wheel serves a dual purpose. It indicates the rotary position of the mandrel and sets the mandrel with the slot therein in a position to receive the wire end, and also provides an audible indication of revolutions of the mandrel. The length of wire required to fill the slot length and to wind up on the mandrel during the initial turn may readily be determined by trial, and then each additional revolution will wind the length of wire determined by the circumference of the mandrel. After a number of counted revolutions the wire is cut and the length of wire remaining yet to be wound will be a constant length, namely the distance between the mandrel contact point and the cutter blade edge. Thus it is simple to produce uniform coils of a predetermined length of wire. For example, the coils referred to in the paragraph above were made by inserting the end of the wire fully in the mandrel slot, turning the hand wheel for five revolutions as indicated by five audible click-stop clicks, cutting the wire and finish winding the coil. A number of the coils produced were weighed to determine uniformity which was found to be within plus or minus 0.2%; this was adequate for the analytical purpose for which they were made. It will be apparent that any predetermined length of coil may be wound depending on the hand wheel revolutions and arrangement of the space distance between the guiding bore and the mandrel.

I claim:

1. Apparatus for winding a coil of wire comprising; a base, a mandrel rotatably mounted on said base and having a slot in one end thereof adapted to receive the end of a length of wire to be wound, means for rotating said mandrel, a follower slidably mounted on said mandrel and biased by spring means toward the said one end of said mandrel, a shaft slidably and rotatably mounted on said base and having an end face adapted to be locked against the said one end of said mandrel thereby to close the open side of the slot in the end thereof, wire guide means

mounted on said base spaced apart from said mandrel, and coil cover guide means fixedly attached to the end of said shaft and projecting therefrom over the side, remote from said wire guide means, of a portion of the said one end of said mandrel when said shaft end face is locked against the said one end of said mandrel.

2. Apparatus for winding a coil of wire comprising; a base, a mandrel rotatably mounted on said base and having a slot in one end thereof adapted to receive the end of a length of wire to be wound, a hand wheel for rotating said mandrel fixedly attached to the other end thereof, a follower slidably mounted on said mandrel and biased by spring means toward the said one end of said mandrel, a shaft slidably and rotatably mounted on said base and having an end face adapted to be locked against the said one end of said mandrel thereby to close the open side of the slot in the end thereof, wire guide means mounted on said base spaced apart from said mandrel, and coil cover guide means fixedly attached to the end of said shaft and projecting therefrom over the side, remote from said wire guide means, of a portion of the said one end of said mandrel when said shaft end face is locked against the said one end of said mandrel.

3. Apparatus for winding a coil of wire comprising; a base, a mandrel rotatably mounted on said base and having a slot in one end thereof adapted to receive the end of a length of wire to be wound, a hand wheel for rotating said mandrel fixedly attached to the other end thereof, means on said hand wheel for indicating the rotary position of said mandrel, a follower slidably mounted on said mandrel and biased by spring means toward the said one end of said mandrel, a shaft slidably and rotatably mounted on said base and having an end face adapted to be locked against the said one end of said mandrel thereby to close the open side of the slot in the end thereof, wire guide means mounted on said base spaced apart from said mandrel, and coil cover guide means fixedly attached to the end of said shaft and projecting therefrom over the side, remote from said wire guide means, of a portion of the said one end of said mandrel when said shaft end face is locked against the said one end of said mandrel.

4. Apparatus for winding a coil of wire comprising; a base, a mandrel rotatably mounted on said base and having a slot in one end thereof adapted to receive the end of a length of wire to be wound, a hand wheel for rotating said mandrel fixedly attached to the other end thereof, a follower slidably mounted on said mandrel and biased by spring means toward the said one end of said mandrel, a shaft slidably and rotatably mounted on said base and having an end face adapted to be locked against the said one end of said mandrel thereby to close the open side of the slot in the end thereof, wire guide means mounted on said base spaced apart from said mandrel, a click-stop on said hand wheel indicating the rotary position of said mandrel when the slot in the end thereof points towards said wire guide means, and coil cover guide means fixedly attached to the end of said shaft and projecting therefrom over the side, remote from said wire guide means, of a portion of the said one end of said mandrel when said shaft end face is locked against the said one end of said mandrel.

5. Apparatus for winding a coil of wire comprising; a base, a mandrel rotatably mounted on said base and having a slot in one end thereof adapted to receive the end of a length of wire to be wound, means for rotating said mandrel, a follower slidably mounted on said mandrel and biased by spring means toward the said one end of said mandrel, a shaft slidably and rotatably mounted on said base and having an end face adapted to be locked against the said one end of said mandrel thereby to close the open side of the slot in the end thereof, wire guide means mounted on said base spaced apart from said mandrel, and coil cover guide means fixedly attached to the end of said shaft and projecting therefrom over the side, re-

mote from said wire guide means, of a portion of the said one end of said mandrel when said shaft end face is locked against the said one end of said mandrel, and said coil cover guide means being rotatable to position aligned with the top of said mandrel when said shaft is rotated and withdrawn away from the position with its end face locked against the end of said mandrel.
